(57) **CLAIM**

The ornamental design for a hood scoop fin, as shown and described.

DESCRIPTION

FIG. 1 is a perspective view a hood scoop fin showing the new design;

FIG. 2 is a first side-elevation of the hood scoop fin; the opposite side view being a mirror image thereof;

FIG. 3 is a first end-elevation view of the hood scoop fin;

FIG. 4 is a second end-elevation view of the hood scoop fin;

FIG. 5 is a top view of the hood scoop fin;

FIG. 6 is a bottom view of the hood scoop fin; and,

FIG. 7 is a perspective view of the hood scoop fin in an example system.

The broken lines shown illustrate portions of the hood scoop fin that form no part of the claimed design. The automobile shown in broken lines in FIG. 5 illustrates environmental structure that forms no part of the claimed design.
